Primary Examiner — Lauren D McVey

(57) **CLAIM**

The ornamental design for a monitor bracket, as shown and described.

DESCRIPTION

FIG. 1 is a right side view of a monitor bracket showing my new design;

FIG. 2 is a left side view thereof;

FIG. 3 is a bottom plan view thereof;

FIG. 4 is a top plan view thereof;

FIG. 5 is a front view thereof;

FIG. 6 is a rear view thereof;

FIG. 7 is a front, right and top side perspective view thereof; and,

FIG. 8 is rear, left and bottom side perspective view thereof.

The broken lines in the drawings illustrate portions of the monitor bracket which form no part of the claimed design.

1 Claim, 8 Drawing Sheets
